UNITED STATES PATENT OFFICE.

BURT A. PETERSON, OF ROCKFORD, ILLINOIS, ASSIGNEE TO HOWARD D. COLMAN,
LUTHER L. MILLER, AND HARRY A. SEVERSON, COPARTNERS DOING BUSINESS AT
ROCKFORD, ILLINOIS, AS BARBER-COLMAN COMPANY.

DOFFER.

1,075,852.

Specification of Letters Patent. Patented Oct. 14, 1913.

Application filed January 6, 1912. Serial No. 669,765.

To all whom it may concern:

Be it known that I, BURT A. PETERSON, a citizen of the United States, residing at Rockford, in the county of Winnebago and State of Illinois, have invented certain new and useful Improvements in Doffers, of which the following is a specification.

Machines for replacing full bobbins upon a spinning frame with empty bobbins are usually provided with rollers arranged to run upon a rail extending along the spinning frame near the spindle rail, and one or more rollers arranged to bear upon a rail or flange extending parallel with and below the spindle rail. The distance of the row of spindles upon the spindle rail from the front edge of said rail varies in different spinning frames. The doffing and donning devices are designed to operate in the vertical plane of the row of spindles, with the center lines of said devices coinciding with the center lines of the spindles. In view of the variable position of the row of spindles, it is necessary to vary the position of the doffer with relation to the spindle rail and the rail or flange below it.

One object of this invention is to provide means for so adjusting the position of the doffer, so that the doffer may be used upon a number of spinning frames varying with respect to the location of the row of spindles.

Another object of the invention is to provide a doffer with guide means to facilitate the positioning of the doffer upon spinning frames.

In the accompanying drawings, Figure 1 is a fragmental front elevation of a doffer embodying the features of my invention. Fig. 1^a is a view illustrating a means for varying the position of the doffer-supporting rail. Fig. 2 is a fragmental side elevation of the doffer, showing it in operative relation to a spinning frame. Fig. 3 is a sectional view taken in the plane of dotted line 3-3 of Fig. 1. Fig. 4 is a section on line 4-4 of Fig. 3. Fig. 5 is a fragmental sectional view of a locking device.

Fig. 2 represents at A a transverse portion of a spinning frame, the ring rail being shown at B, a bobbin at C, the so-called ladder-rail at D, the spindle rail or upper

flange of the ladder rail at E, and the lower flange of the ladder rail at F.

The framework of the doffer may be of any suitable character. The form herein disclosed by way of example consists of an upper section which supports the operating mechanism (not shown) and a lower section which carries the receptacle (not shown) for doffed bobbins. The upper section comprises two tubular columns 1 rigidly united at their lower ends by a transverse bracket or frame-member 2.

3 is a downwardly-extending bracket fixed to the lower side of the frame-member 2.

The upper section is suspended upon the spinning frame by means including a suitable number of grooved rollers 4 mounted upon a bar 5 attached to the frame-member 2, said rollers running upon a channel rail G fixed to the spinning frame adjacent to the spindle rail.

The channel rail G is secured in place by any suitable means, such as a suitable number of clips H attached to the rail G and sprung over the rail E. When the distance between the center line of the row of spindles and the front edge of the spindle rail E is less than the standard distance, a shim J of proper thickness is placed between the front edge of said rail E and the part of the clip which engages the rail G.

Upon the bracket 3 is a roller 6 arranged to bear against the forward edge of the rail F and thereby maintain the doffer in stable equilibrium and in vertical position. In order to compensate for variations in the position of the rail G in different spinning frames, I provide means for adjusting the position of the stabilizing roller 6. Herein I have shown the roller 6 as rotatably mounted between a flange or collar 7 and a washer 8 on a vertical spindle 9. Said spindle extends through an opening 10 in a slide 11 and through a slot 12 in the portion 13 of the bracket 3. The spindle 9 is supported from the bracket-portion 13 by means of a nut 14 turned on the upper screw-threaded end of the spindle. A spring 15 tends to move the slide 11, the spindle 9 and the roller 6 forwardly. The means herein shown for moving the slide, spindle and roller in the opposite direction com-

prises a wedge 16 guided for movement in an opening 17 intersecting the slot 12 at right angles, said wedge lying between the spindle 9 and one wall of the guide opening 17.

In the form herein shown, the means for moving the wedge 16 consists of a lever 18 pivoted at the side of the doffer as at 19 on the bar 5, and a link 20 connecting the lever 18 and the wedge. The wedge may be locked in adjusted position in any suitable way, as by means of a projection 21 on the lever 18 adapted to enter any one of a plurality of recesses 22 in a locking plate 23. The lever 18 possesses sufficient resiliency to retain the projection 21 in a recess 22 until the lever is forced to one side or the other. The upper end of the lever is within convenient reach of the operator.

20 The lower section of the doffer consists, in the example selected for illustration, of a rigid frame-work comprising two columns 24 slidably mounted within the tubular columns 1, the lower ends of the columns 24 being connected by a bracket 25. To said bracket are fixed bars 26 forming a frame to receive and support a box (not shown) for the doffed bobbins. The lower section of the doffer is supported upon the floor by 30 suitable means such as rollers 27. The upper section may be moved with relation to the lower section by means of a rock shaft 28 supported in the frame-member 2, a hand lever 29 and a crank arm 30 fixed to the shaft 28, and links 31 connecting the lever and the crank arm with the bracket 25.

32 are two guide-plates or stops fixed to and projecting below the bar 5, the inner or rear faces of the guide-plates being in 40 the vertical plane of the grooves in the rollers 4. In placing the doffer in operative relation to the spinning frame, the upper section is raised by depressing the hand lever 29 until the rollers 4 are above the horizontal plane of the rail G. The doffer is then 45 pushed toward the spinning frame until the guide-plates stop against the forward edge of the rail G, whereupon the operator lowers the upper section until the rollers 4 stand on said rail.

When installing the doffer in a spinning room, any required number of locking recesses 22 are drilled in the plate 23 in such 55 locations as to provide a proper adjustment of the roller 6 for each frame on which the doffer is to be used.

The doffer may be propelled along the spinning frame by any preferred means, as, for example, that shown in Patent No.

983,858, issued February 7, 1911, upon an 60 application filed by Howard D. Colman and myself.

I claim as my invention:

1. In a doffer, a doffer framework, supporting means on the framework, other supporting means on the framework below the first mentioned supporting means, means for adjusting the second mentioned supporting means, and a hand lever pivoted at the side of the doffer framework, and connected at its lower end to the adjusting means.

2. In a doffer, a doffer framework, suspending means on the framework, stabilizing means on the framework below the suspending means, means for adjusting the stabilizing means, and a hand lever pivoted at the side of the doffer framework and connected to the adjusting means.

3. In a doffer, a doffer framework, suspending means and stabilizing means on the framework, a wedge arranged to adjust the stabilizing means, and a hand lever mounted on the doffer framework and operatively connected to the wedge for moving the latter.

4. In a doffer, a framework comprising an upper section and a lower section slidably connected together; suspending means on the upper section; stabilizing means on the upper section below the suspending means, and a hand lever pivoted on the upper section and connected to the stabilizing means for adjusting the latter.

5. In a doffer, an upper section and a lower section slidably connected together, means for raising the upper section, a supporting roller on the upper section adapted to run upon a spinning-frame rail, and a doffer-positioning stop on the upper section below the roller and in position to contact such a rail when the roller is properly positioned above the rail.

6. In a doffer, a doffer framework, suspending means and stabilizing means on the framework, means to adjust the stabilizing means, a hand lever pivoted at the side of the doffer framework and connected to the adjusting means for operating the latter, and means for locking the hand lever in various positions.

In testimony whereof I affix my signature in presence of two witnesses.

BURT A. PETERSON.
